US00D776347S

(12) **United States Design Patent** (10) Patent No.: **US D776,347 S**
(45) Date of Patent: **** Jan. 10, 2017**

(54) **EPILATOR**

(71) Applicant: **Braun GmbH**, Kronberg (DE)

(72) Inventors: **Frieder Grieshaber**, Neu-Anspach (DE); **Bjorn Kling**, Glashutten (DE); **Tarik Mehaddene**, Karben (DE); **Markus Halm**, Bad Homburg (DE); **Tobias Schwarz**, Schmitten (DE)

(73) Assignee: **Braun GmbH**, Kronberg (DE)

(**) Term: **15 Years**

(21) Appl. No.: **29/568,206**

(22) Filed: **Jun. 16, 2016**

Related U.S. Application Data

(62) Division of application No. 29/483,745, filed on Mar. 3, 2014, now Pat. No. Des. 763,505.
